ISAIAH HALL, OF BIRMINGHAM, ENGLAND

THERMOSTATIC REGULATING DEVICE

1,128,778.

Specification of Letters Patent. Patented Feb. 16, 1915.

Application filed September 16, 1913. Serial No. 790,046.

To all whom it may concern:

Be it known that I, ISAIAH HALL, a subject of the King of Great Britain, residing at Exchange Buildings, New street, Birmingham, England, have invented a new and useful Thermostatic Regulating Device; and I do hereby declare the following to be a full, clear, and exact description of the same.

10 This invention relates to furnaces for melting metal, more especially such as are used for the melting of used metal, cleansing it and subsequently casting it; and is particularly adapted for use in the melting of 15 type metal.

The object of this invention is to provide a furnace comprising means for regulating and also if desired for indicating the temperature of the molten material.

20 In the accompanying drawings forming a part hereof:—Figure 1 is a view illustrating the temperature regulating and indicating device and showing the gas supply box with the cover removed. Fig. 2 is a 25 vertical section at A—B in Fig. 4. Fig. 3 is a longitudinal section through the controlling members which are exposed to the metal of the furnace. Fig. 4 illustrates the indicating mechanism with the dial plate 30 removed.

In carrying my invention into practice as illustrated upon the accompanying drawings gas is supplied by the pipe 18, and passes through the valve seating 19 and into 35 the chest 20 when the valve 21 is away from the seating, the gas passing out from the chest by way of the pipe 22 to the burner which is to be regulated in accordance with the variation in the temperature of the 40 material which is exposed to the heating influence of such burner.

The chest is preferably made of aluminum and carries a cover plate 28 which is secured to the chest by screws taken into 45 holes 23 whereby the chest is sealed in a gas tight manner. The chest carries two levers one of which 24 is pivotally mounted at 23 having a short length at the left hand end and a long length at the right hand end 50 so arranged that a small movement of the former gives a large movement at the right hand end. Parallel with this first lever is a second lever 26 pivoted at its end 27 and carrying at its opposite end a valve 21 this 55 lever 26 being supported upon the lever 24 by a projecting pin 29, while the lever 24

is normally raised by the spring 30. It will thus be seen that when the left hand end of the lever 24 receives a slight movement say a falling movement the right hand end of 60 the lever will rise lifting the lever 26 the left hand end of which rises but with a much greater movement bringing the valve 28 toward its seating and it may entirely close the valve if the movement is sufficient, 65 leaving only a small passage or port for keeping the burner alight, which passage may be adjustable in area if so desired.

Immediately beneath the left hand end of the lever 24 is a tube 31 which dips into the 70 metal pot, this tube being provided with a closure plug 32. Within this tube is a stick 33 of graphite, carbon, plumbago or the like, non-metallic refractory material having a 75 relatively small co-efficient of expansion compared with the co-efficient of expansion of the metal tube and above this carbon stick is a metal rod 34 the upper end of which abuts against the under edge of the left hand portion of the lever 24, while the lower edge 80 rests upon the top of the carbon stick 33. Around this metal rod is a spring 35 abutting against the collar 36, and the bottom of the chest, this spring maintaining the rod and the carbon against the plug 32. 85

As previously stated the lower end of the tube 31 dips into the molten metal in the metal pot and it will be obvious that the tube and the carbon stick will expand according to the temperature of the molten 90 metal, but as the tube is of metal of a higher co-efficient of expansion than the carbon stick it will be obvious that the effect will be to lower the top end of the metal rod 34 which will allow the left hand end of the 95 lever 24 to fall under the influence of the spring 30 thus tending to close the valve as the temperature in the metal pot rises and opening the valve when the temperature falls. 100

The valve seating 19 is adjustable under the influence of the screw 37 controlled by the head 38, which screws into a bar extending across the inside of the valve seating while the head is held against upward movement by the retaining member 39 so that when the screw is rotated the valve seating is raised or lowered to increase or decrease the valve opening thus providing a hand adjustment or regulation. 105

Means may be provided for opening the valve by hand or regulating by hand such 110

as the screw 50 abutting against the upper edge of the lever 26 and whereby said lever may be depressed.

The temperature indicating mechanism is contained in a casing 40 and is controlled by a rod 41, the lower end of which rests on the right hand end of the lever 24. The casing includes a dial plate in the center of which is a shaft 42 carrying an indicating pointer 43 and to this shaft is also connected a crank 44. Pivoted to the casing at 45 is a lever 46 which is connected to the crank 44 by a link 47 in such manner that when the left hand end of the lever 46 is raised the crank is moved to rotate the shaft 42 and the indicating pointer 43. Immediately above the rod 41 is a pivoted member 48 one extremity of which abuts against the left hand end of said lever 46, being so arranged that when the rod 41 rises, the lever 46 is operated to move the indicator, said lever being returned to its initial position by the spring 49.

The indicating dial is calibrated according to the temperature range for which the apparatus is to be used so that as the temperature rises and falls the rod 31 will move, indicating such temperatures.

Instead of the link and lever mechanism for controlling the indicator illustrated in Fig. 1 any other equivalent arrangement might be used.

What I claim is:—

1. In a thermostatic regulating device, the combination of a gas chamber; a differential expansion device extending from the gas chamber; a lever pivoted within said gas chamber having its short end in contact with said differential expansion device; an abutment carried by the long end of said lever; a spring controlling said lever and retaining said short end in engagement with the differential expansion device; a second lever pivoted at one end and engaged by said abutment; a sliding rod abutting against one of said levers; a visual indicating device controlled by said sliding rod responding to changes in the position of the said lever and serving to show the temperature within the furnace; a valve seating; and a valve carried by said second lever.

2. In a thermostatic regulating device the combination of a gas chamber; a differential expansion device extending from the gas chamber; a lever pivoted within said gas chamber having its short end in contact with said differential expansion device; a second lever pivoted at one end and engaged by said lever; a sliding rod abutting against one of said levers; a visual indicating device controlled by said sliding rod responding to changes in the position of the said lever and serving to show the temperature within the furnace; a valve seating; and a valve carried by said second lever.

3. In a thermostatic regulating device the combination of a gas chamber; a metal tube extending from the gas chamber; a stick of non-metallic refractory material having a different co-efficient of expansion to the metallic tube and located inside said tube; a metal rod located within said tube abutting against the end of the said refractory stick and having its opposite end projecting into said gas chamber; a spring disposed around said metal rod and retaining said rod in contact with the said refractory stick; a lever pivoted within said gas chamber having its short end in contact with the end of the said metal rod; an abutment carried by the long end of said lever; a spring controlling said lever and retaining said short end in engagement with the metal rod; a second lever pivoted at one end and engaged by said abutment; a valve seating adjustable within said gas chamber; a screw engaging said valve seating; a head on said screw located exteriorly of said gas chamber and serving when rotated to adjust the position of the said valve seating; a valve carried by said second lever; an adjustable screwed rod for preventing complete closure of the valve; a sliding rod abutting against one of said levers; and a visual indicating device controlled by said sliding rod responding to changes in the position of the said levers and serving to show the temperature within the furnace.

4. In a thermostatic regulating device, the combination of a gas chamber; a valve; means for adjusting the position of the valve seating to enable the moment of "cut off" to be set as desired; a pivoted lever carrying said valve; a spring connected to said lever tending to close the valve; a second pivoted lever engaging the first lever; a metal tube extending from the gas chamber into the furnace; a stick of non-metallic refractory material having a different co-efficient of expansion to the metal tube and located inside said tube; a metal rod located between the end of said stick and the second lever aforementioned so arranged that the valve opens and closes as the temperature in the metal furnace falls and rises respectively; an indicating device; a pointer carried by a shaft; a rod resting upon the aforementioned lever carrying the valve and a system of levers having movement responsive to the movement of the valve carrying lever and serving to control the position of the pointer.

5. In a thermostatic regulating device, the combination of a gas chamber; a valve; means for adjusting the position of the valve seating operative while the furnace and gas supply are in use for enabling the moment of "cut off" to be set as desired; a pivoted lever carrying said valve; a spring connected to said lever tending to close the

valve; a second pivoted lever engaging the first lever; a metal tube extending from the gas chamber; a stick of non-metallic refractory material having a different coefficient of expansion to the metal tube and located inside said tube; and a metal rod located between the end of said stick and the second lever aforementioned so arranged that the valve opens and closes as the tem-

perature in the metal furnace falls and rises respectively.

In testimony whereof, I have signed my name to this specification in the presence of two subscribing witnesses.

SAIAH HALL.
